(57) CLAIM

The ornamental design for a foam pogo stick, as shown and described.

DESCRIPTION

FIG. 1 is a front perspective view of a pogo stick in accordance with the present invention;

FIG. 2 is a front elevational view of the present invention (the rear side is mirror image of the front side);

FIG. 3 is a right side elevational view of the present invention (the left side is mirror image of the right side);

FIG. 4 is a top plan view of the present invention;

FIG. 5 is a bottom plan view of the present invention; and,

FIG. 6 is a front perspective view in accordance with a second embodiment of the present invention (the only difference between this embodiment and the first embodiment in FIGS. 1-5 is the handles being proportionally smaller and smooth rather than stepped, all other features being the same as the first embodiment of FIGS. 1-5).
